CLAIM

The ornamental design for an electronic device design, as shown and described.

DESCRIPTION

FIG. 1 is a perspective front view of an electronic device design showing our new design;

FIG. 2 is a perspective back view thereof;

FIG. 3 is a front elevation view thereof;

FIG. 4 is a back elevation view thereof;

FIG. 5 is a side elevation view thereof;

FIG. 6 is another side elevation view thereof;

FIG. 7 is a top plan view thereof; and,

FIG. 8 is a bottom plan view thereof.

In the drawings, the broken lines depict environmental subject matter only and form no part of the claimed design.
